Patented July 20, 1920.

2 SHEETS—SHEET 2.

UNITED STATES PATENT OFFICE.

HERMAN C. DREIS, OF CHICAGO, ILLINOIS.

BENDING-BRAKE.

1,347,474.

Specification of Letters Patent. Patented July 20, 1920.

Application filed September 22, 1919. Serial No. 325,439.

To all whom it may concern:

Be it known that I, HERMAN C. DREIS, a citizen of the United States, and a resident of Chicago, in the county of Cook and State 5 of Illinois, have invented certain new and useful Improvements in Bending-Brakes, of which the following, when taken in connection with the drawings accompanying and forming a part hereof, is a full and complete specification.

This invention relates to brakes used for bending sheet metal.

Among the objects of the invention are to obtain a bending brake in which the bed, 15 the upper jaw member, and the apron, respectively, will not bend or give when put under heavy pressure, as in the bending of a comparatively thick sheet of metal, or a long one, to insure a straight line to said 20 bend.

A construction whereby the objects sought by me are obtained is illustrated in the drawings referred to, in which—

Figure 1 is a perspective of a brake embodying the invention;

Fig. 2 is a front elevation of the apron of the brake illustrated in Fig. 1.

Fig. 3 is an elevation of the lower edge of one end of said apron.

Fig. 4 is a vertical sectional view on an enlarged scale, of a portion of the apron, the lower and the upper jaw of the brake; and

Fig. 5 is an elevation on line 5—5 of Fig. 35 4, viewed in the direction indicated by arrows.

A reference character applied to designate a given part indicates said part throughout the several figures of the drawings where- 40 ever the same appears.

A represents the ends or standards of the brake; and B the lower jaw, (see Figs. 4 and 5). C represents the apron; and D the upper jaw.

The lower jaw, (Figs. 4 and 5), comprises 45 a floating member, having the horizontal part b, and the vertical part b¹, hereinafter termed floating plates, that being the trade name by which they are known, which in 50 the construction illustrating the invention, are joined by the angle iron E and bolts e, e¹.

F represents the bar which forms the gripping member of the lower jaw. Member F is joined to the members b, b¹, as by said 55 bolts e, e¹. The lower jaw also comprises the plates G, G¹, which are connected or joined

together by angle iron H and bolts h, h. Plate G is rigidly secured to the ends or standards A, by bolts g, g, and the vertical plate G¹ is also rigidly secured to said standards by bolts g¹, g¹. The floating plate b is maintained in spaced relation to plate G by blocks I, I, which are held in corresponding recesses in said plates b and G, and bolts J, J, and the floating plate b¹ is maintained in similar spaced relation to vertical plate b¹ by blocks I¹, I¹, and bolts J¹, J¹. 60 65

Blocks I, I, and I¹, I¹, are disposed or positioned between plates b, G, and b¹, G¹, at a distance from the ends and sides of plates b, b¹, respectively, which permits said ends and sides to move, under pressure, relative to the plates b¹, and G¹, said position corresponding to the position of said blocks in the upper jaw and apron, as illustrated in Fig. 1. The ends of said plates b, b¹ do not extend to the ends of plates G, G¹, or to the standards A, the ones of said ends which are illustrated in Fig. 5 being designated by the reference character X, X. 70 75 80

The upper jaw, D, comprises ends K, K, which are adjustably mounted in standards A, A, in the ordinary way, as by pin L in slot l of member M; the plates N, N¹, which are secured to said ends, as by bolts n, n; 85 and to each other, at the meeting sides or edges thereof, by angle iron O and rivets O¹, O¹; the floating plates P, P¹; the blocks I, I¹, and bolts J, J¹. Blocks I, I¹, and bolts J, J¹, maintain members P, P¹, herein- 90 after termed floating plates for the reasons given relative to members b, b¹ in spaced relation to plates N, N¹, in a corresponding manner to the maintenance of plates b, b¹, to plates G, G¹. F¹ represents the 95 bar which forms the gripping member of the upper, and said bar is rigidly attached to plates P, P¹.

Apron C comprises ends Q, Q, which are pivoted on fulcrums q, q, in the ordinary 100 manner, the plate R, which is secured to said ends Q, Q, as by bolts r, r, and the member R¹, hereinafter termed a floating plate for the reasons given relative to plates b, b¹ and P, P¹, the blocks I¹, I¹, and bolts J¹, J¹. Blocks 105 I¹, I¹, and bolts J¹, J¹, maintain floating plate R¹ in spaced relation to plate R, in a corresponding manner to the maintenance of plates b, b¹, to plates G, G¹.

By the hereinbefore described construction of the upper and lower jaws, and of the apron, of the brake, a plate, as Y, Fig. 1, is 110

firmly gripped and held, throughout its entire length, by the gripping members F, F¹, of said jaws; the pressure applied to said gripping bars being transmitted to the floating plates b, b¹ of the lower jaw and P, P¹, of the upper jaw; and by said floating plates, (through blocks I, I¹), transmitted to the plates G, G¹, and N, N¹; and the bend made to said plate Y upon turning the 10 apron on its fulcrums q, q, is on a straight line, or (in case a comparatively thick plate relative to the size of the brake is bent), on a substantially straight line.

The pressure received and transmitted by 15 the several blocks I, I¹, is received by the several supporting members G, G¹, N, N¹, and R, at a plurality of places, which are, respectively, at pre-determined distances from the respective ends thereof, in no instance 20 midway of said supporting members; and any depression of said supporting members due to force applied through said blocks depresses the blocks substantially equally; so that said blocks on a given supporting member are, at all times, in substantially 25 the same plane, and what are hereinbefore termed the floating plates are thus respectively, supported by a plurality of blocks which are, as stated, in substantially 30 the same plane, said floating plates, being so supported at predetermined distances from the ends thereof and in a plurality of places (and not midway thereof), the pressure applied thereto is distributed over comparatively 35 small areas, relative to the total area of the plates, thus effecting, as stated slight deflection of said plates from a true plane.

The operation of the brake is similar to 40 the operation of brakes heretofore made, except so far as set forth in the preceding paragraph.

I claim:

1. In a bending brake, an apron consisting 45 of pivoted end members, in combination with a plate arranged to form a supporting member secured at its ends to said end members, an additional plate member, and means, between the ends thereof, to support said 50 additional member in spaced relation to said supporting member.

2. In a bending brake, an upper jaw, a lower jaw, and an apron, respectively comprising a plate arranged to form a supporting member, and means to support the ends of said supporting member, said means in said apron consisting of pivoted end members, in combination with an additional plate member, and means positioned between 60 the ends of said additional member to support it in spaced relation to said supporting member.

3. The combination of a plate supported 65 at its ends, an additional plate, said plates respectively provided with a plurality of

oppositely positioned recesses between the ends and the transverse central lines thereof, blocks in said recesses arranged to position said plates in parallel planes and in spaced relation, means to maintain said plates as 70 positioned, said means adapted to permit variation in said spaced relation, and means to apply pressure to said additional plate.

4. The combination of a plate rigidly secured in a horizontal plane at its ends to a 75 standard, a standard, an additional plate, said plates provided with a plurality of recesses between the ends and the transverse central lines thereof, blocks in said recesses, and means to maintain said plates in parallel planes and in spaced relation with said blocks interposed between them, said additional plate movable independently of the movement of said first named plate to vary 80 said spaced relation, and means to apply pressure to said additional plate.

5. Plates, means to support said plates at the ends thereof, said plates joined at meeting sides, in combination with additional plates and means to maintain said additional plates in spaced relation to said first named plates and in parallel planes, said means including blocks between said additional and first named plates, and bolts, said bolts being adapted and said blocks being 90 positioned to permit said additional plates to move relative to said first named plates and independently thereof upon pressure being applied to said additional plates.

6. In a bending brake, an upper and a 100 lower jaw, respectively comprising a horizontal and an additional plate joined at the meeting sides thereof, said joining including angle irons and bolts, means to support the ends of said plates, additional plates secured 105 to said first named plates in spaced relation thereto and free to move independently thereof to vary said spaced relation, and gripping members attached to said additional plates, in combination with an apron 110 fulcrumed on said supporting means, said apron comprising a plate, fulcrumed members, said plate and said fulcrumed members rigidly secured together, and an additional plate secured in spaced relation to 115 said rigidly secured plate and free to move independently thereof to vary said spaced relation.

7. In a bending brake, an upper and a lower jaw, respectively including a horizontal 120 and an additional plate, means to join said plates at the meeting edges thereof, said means including angle irons and bolts, and means to support said plates at the ends thereof, additional plates, all said plates respectively provided with recesses, blocks and bolts, said blocks positioned in said recesses, and said blocks and bolts arranged to maintain said additional plates in spaced relation to said first named plates and free to 125 130

move independently thereof to vary said spaced relation, and gripping members attached to said additional plates, in combination with an apron fulcrumed on said means 5 to support, said apron including a plate, fulcrum members, said plate and said fulcrum members rigidly attached together, an additional plate, blocks and bolts, said blocks and bolts arranged to secure said additional

plate to said rigidly secured plate in spaced 10 relation thereto and free to move independently of a bend therein to vary said spaced relation.

HERMAN C. DREIS.
